EDWARD P. CORCORAN AND WALTER B. HADLEY, OF CHICAGO, ILLINOIS, ASSIGNORS TO
JOHN L. KELLOGG, OF CHICAGO, ILLINOIS

DEFIBERIZING MACHINE

Application filed January 20, 1931. Serial No. 510,051.

This invention relates to improvements in defiberizing machines, particularly in machines for defiberizing wood for use in making paper.

5 The main object of this invention is to provide means for adjusting the position of the defiberizer brushes in an efficient and dependable manner.

Machines of the type herein referred to 10 usually comprise a table, a pair of brushes mounted on shafts extending transversely of the machine, under the table, and means for driving the shafts in opposite directions. The table has an opening located above each brush, 15 extending through the table top from approximately one side margin to the other, each of said openings being wide enough to permit the tips of the brush needles to extend into the opening and to engage the material to be defiberized, which is piled on the table and supported thereon so as to extend across the openings. 20 The material to be defiberized is held in an open bottom hopper which is adapted to be moved back and forth on the table and carries the material with it across the openings.

In using machines of the character described, considerable trouble has been experienced in retaining the brushes in adjusted position for efficient engagement with the material to be defiberized. On account of the speed of operation of the machine, considerable vibration is set up and it has been noted that by reason of the brushes moving out of adjusted position, the production of defiberized material is substantially lessened within about thirty minutes after adjustment.

The object of the present invention is to remedy this difficulty and to produce a machine efficient for its intended purpose.

40 In the drawing—

Fig. 1 is a side elevation, partly in section, of a defiberizing machine embodying our invention.

Fig. 2 is a plan view of the brush adjusting means, which is the subject of this invention.

Fig. 3 is an enlarged side elevation of the adjusting means.

In that embodiment of the invention shown 50 in the drawing, 10 indicates the base of the

machine, 11 the frame, 12 the table or horizontal support, 13 a hopper adapted to be moved back and forth on the table, 14 the rails or guides on which the hopper wheels 15 travel, and 16 any suitable means (not fully shown) 55 for reciprocating the hopper.

Under the table are two brush shafts 17 mounted in brush bearing housings 18. The brush needles are indicated at 19 and a motor for driving the brushes, at 20.

The table 12 is provided with rectangularly shaped openings 21 located above the brushes 19. The material to be defiberized is placed in the hopper on top of the table 12, to extend across the openings 21 in position to be engaged by the tips of the brush needles 19.

The brush housing 18 is provided with a lateral ear 22 apertured to receive the pivot pin or bolt 23 which secures the housing to the upright support 24. Directly opposite 70 the ear 22 the housing 18 is provided with a slotted ear 25 through which a bolt 26 extends into a fixed part of the frame work such as the depending boss 27. Upper and lower screw bolts 28, 29, extend through the 75 ear 25 and engage the bolt 26 at opposite sides. Nuts 30, 31 on the bolts 28, 29, respectively, engage the ear 25 on its upper and lower edges. By turning the nut 31 on the bolt 29 and the nut 30 on the bolt 28, the brush bearing housing 18 may be raised or lowered about the pivotal connection 23.

It has been found that adjusting means of the type described cannot be depended upon to retain the brushes in adjusted position for any substantial period of time. In the operation of the machine, the friction on the brush needles as well as the normal vibration of the parts, due to the speed of operation, causes the brushes to slip downwardly 85 about their pivotal mountings with the result that production is retarded. For this reason we have provided an attachment which may be installed in conventional machines. It comprises a side bar 32, preferably 90 in the form an angle bar, having downturned ends 33 riveted or otherwise secured to the upright standards 24. The upper surface of the bar 32 is located adjacent the lower surface of the brush bearing housing 18. Ad- 100

jacent one of the supports 24 and slightly above the top of the bar 32, fixed to the frame 11, is an L-shaped bracket comprising plates 34 and 35. The plate 35 is apertured to receive a wedge member 36 which has a flat 5 bottom surface adapted to rest on the bar 32 and an inclined or tapered wedge upper surface 37. Opposite the tapered end the wedge is screw threaded as indicated at 38.

10 The standard 24 is apertured in horizontal alignment with the aperture in the bracket plate 35 to accommodate the wedge which extends therethrough. Lock nuts 39 and 40, on the screw threaded part of the wedge, hold it in adjusted position relatively to the bracket plate 35. If desired the horizontal bar 32 and a member extending at right angles thereto, such as the bracket plate 35, may be made integral and secured to a fixed part 15 of the machine.

20 The wedge 36 may be of any desired size to suit the machine with which it is to be used, but usually a wedge $1\frac{1}{8}$ " thick, tapering down to $\frac{5}{8}$ " in thickness is sufficient for its intended purpose. After the wedge has been 25 placed into the desired position under the brush bearing housing so as to bring the brush needles into proper engagement with the material to be defiberized, the lock nuts 39 and 40 are tightened to retain it in adjusted position.

When the adjusting means of the present invention is installed in a conventional machine of the type herein shown, the adjusting means consisting of the parts numbered 30 25 to 31 inclusive may be dispensed with, or if desired, may be used in addition to the adjusting means of the present invention.

35 The supporting means for the wedge may be installed at each side of the machine and wedge members may be used at one or both ends of each brush. The lock nuts cooperating with the wedge member and part of the fixed support have been found a convenient 40 means for retaining the wedge in adjusted position, but obviously other means such as apertures in the wedge end and cotter pins associated therewith, may be substituted for the construction herein shown.

45 Changes may be made in details of construction without departing from the scope of my invention and I do not intend to be limited to the exact form shown and described except as set forth in the appended 50 claims.

We claim—

1. A defiberizing machine comprising a table, upright supports for the table, a brush bearing housing pivotally mounted on the 55 upright supports, a brush having a shaft rotatably mounted in the housing, and means for adjusting the position of the housing relatively to the table, said means comprising a cross bar secured to the upright supports, 60 an apertured bracket secured to a fixed part

of the machine, a wedge member movable on said cross bar contacting the brush bearing housing and means on the wedge member cooperating with the bracket for retaining the wedge in adjusted position.

2. A defiberizing machine comprising a table, upright supports for the table, a brush bearing housing pivotally mounted on the upright supports, a brush having a shaft rotatably mounted in the housing, and means for adjusting the position of the housing relatively to the table, said means comprising a cross bar secured to the upright supports, an apertured bracket secured to a fixed part of the machine, a wedge member movable on said cross bar contacting the brush bearing housing and means on the wedge member cooperating with the bracket for retaining the wedge in adjusted position, said last mentioned means consisting of screw threads on the end of the wedge member and lock nuts on the screw threaded end, one at each side of the bracket.

3. An adjusting attachment for a pivoted brush bearing housing of a defiberizing machine, comprising a cross bar adapted for attachment to a fixed part of the machine, an apertured piece extending at right angles to the cross bar, a wedge member contacting the housing movable on the bar, and having one end extending through the apertured piece and means cooperating with said apertured piece to retain the wedge member in adjusted position on the cross bar.

In testimony, that we claim the foregoing as our invention, we affix our signatures, this 16th day of January, 1931.

EDW. P. CORCORAN.
